UNITED STATES PATENT OFFICE.

ALFRED D. TETREAU AND ALBERT TETREAU, OF SANFORD, MAINE.

FILLING-STRIPPER FOR LOOMS.

1,333,098.

Specification of Letters Patent.

Patented Mar. 9, 1920.

Application filed September 24, 1919. Serial No. 325,884.

To all whom it may concern:

Be it known that we, ALFRED D. TETREAU and ALBERT TETREAU, citizens of the United States, residing at Sanford, in the county of York and State of Maine, have invented certain new and useful Improvements in Filling-Strippers for Looms, of which the following is a specification.

Our invention relates to looms, particularly to attachments therefor, and has for its object the provision of a device whereby the filling or last layer or so of thread upon the loom bobbins may be caught and wound onto a receiving bobbin without the necessity of cutting the filling.

An important and more specific object is the provision of a rotary shaft mounted upon a loom and driven by the mechanism thereof and a normally contracted bobbin 20 engaged upon and held in expanded position by the shaft for receiving the filling, the bobbin being so constructed that when removed from the shaft it will contract to permit the filling wound thereon to slide off.

Another object is the provision of a device of this character which will be simple and inexpensive in manufacture, easy to install, efficient and durable in service, and a general improvement in the art.

With the above and other objects and advantages in view, the invention consists in the details of construction to be hereinafter more fully described and claimed, and illustrated in the accompanying drawings, in

which

Figure 1 is an elevation of the device,

Fig. 2 is an elevation of the bobbin removed, and

Fig. 3 is a cross sectional view through 40 the bobbin on the line 3—3 of Fig. 2.

Referring more particularly to the drawings, the letter A designates a portion of the frame of a Stafford loom. In carrying out our invention, we provide a block 10 secured upon the frame A by a suitable bolt 11 which also serves to secure upon the block 10 a bearing bracket 12. Also secured upon the frame A in spaced relation to the block 10 is a bracket 13 held by a suitable bolt 14.

50 Journaled through the bracket 13 is a shaft 15 which is provided at one end with a reduced extension 16 journaled in the bracket 12 and which has its other end free and tapered as shown at 17. A collar 18 is secured upon the shaft 15 and bears against

the bracket 13 for preventing longitudinal movement of the shaft. Also secured upon the shaft between the brackets 12 and 13 is a flanged pulley 19 about which is trained a belt 20 trained over a suitable pulley on a 60 shaft (not shown) of the loom mechanism. By this means the shaft 15 is rotated.

In conjunction with the mechanism above described we use a bobbin designated broadly by the numeral 21 and this bobbin 65 is formed from a tapered shell 22 longitudinally split at intervals as shown at 23 and provided at one end, the larger, with a flange 24. By this construction the bobbin, which may be of thin wood or metal, is expanded though it is normally in contracted form as shown in Figs. 2 and 3.

In the use of the device, the smaller end of the bobbin is slipped onto the free end of the shaft 15 and slid onto the tapered portion of the shaft whereupon the bobbin will be expanded into cylindrical form, as shown in Fig. 1. The filling or last layer or so of thread remaining on a bobbin (not shown) of the loom, is then led onto the bobbin 22 80 and as this bobbin 22 is rotated by the mechanism previously described, the filling will be wound thereon. When the bobbin 22 is filled, it is slid off from the shaft 15, whereupon, owing to its natural tendency, the 85 bobbin 22 will contract so that the thread or filling wound thereonto may be readily slipped off.

From the foregoing description and a study of the drawings, it will be apparent 90 that we have thus provided a very simple and efficient power driven filling stripping device which is readily operable, which will be a great time and labor saver in removing the filling without cutting it and which 95 will efficiently perform all the functions for which it is intended.

While we have shown and described the preferred embodiment of the invention, it will of course be readily understood that 100 we reserve the right to make such changes in the form, construction, and arrangement of parts as will not depart from the spirit of the invention or the scope of the subjoined claims.

Having thus described our invention, we claim:

1. A filling stripper comprising a rotary shaft and a bobbin disposed thereon and adapted to have thread wound thereonto, 110

the bobbin having a normally contracted core held in expanded position by its engagement upon said shaft.

2. A device of the character described comprising a rotary shaft having a tapered free end, in combination with a bobbin having a normally contractile core engaged upon said shaft and expanded by its engagement over said tapered end.

10 3. A device of the character described comprising a rotary shaft having a tapered free end, and a bobbin engageable upon the

shaft by sliding over said tapered end, said bobbin being formed as a tapered body slit longitudinally and normally contracted whereby upon disengagement of the bobbin from the shaft the core will contract to permit sliding off of the filling wound thereonto.

In testimony whereof we hereto affix our 20 signatures.

ALFRED D. TETREAU.
ALBERT TETREAU.
